[57] CLAIM

The ornamental design for a lifting jack, as shown and described.

DESCRIPTION

FIG. 1 is a front and side perspective view of a lifting jack showing my new design;

FIG. 2 is a top, rear and side perspective view thereof; FIG. 3 is a side elevational view thereof, the opposite side elevational view being a mirror image of that shown;

FIG. 4 is an exploded front perspective view of the lifting assembly. The reaming portion of the lifting jack being omitted for convenience of illustration; and, FIG. 5 is a top plan view thereof.
